[57] CLAIM

The ornamental design for the cigar boring device, as shown and described.

DESCRIPTION

FIG. 1 is a perspective view of a cigar boring device showing my new design;

FIG. 2 is a front elevational view thereof, the rear elevational view being the same as said front elevational view;

FIG. 3 is a top plan view thereof, the bottom plan view being the same as said top plan view;

FIG. 4 is a right side elevational view thereof;

FIG. 5 is a left side elevational view thereof;

FIG. 6 is a front elevational view of a second embodiment of my design, the rear elevational view being the same as said front elevational view, and the top and bottom plan views being the same as in FIG. 3 absent the surface ornamentation on the right section thereof;

FIG. 7 is a right side elevational view of said second embodiment, the left side elevational view being the same as shown in FIG. 5;

FIG. 8 is a perspective view of an open cigar boring device showing my new design in the first embodiment;

FIG. 10 is a right side elevational view of said left section thereof, and the left side elevational view being the same as shown in FIG. 5;

FIG. 11 is a left side elevational view of said right section thereof, and the right side elevational view thereof being the same as shown in FIG. 4;

FIG. 12 shows the cigar boring device of the first embodiment with a ring attached thereto;

FIG. 13 shows the open cigar boring device of the first embodiment with a ring attached thereto;

FIG. 14 shows the cigar boring device of the second embodiment with a ring attached thereto; and,

FIG. 15 shows the open cigar boring device of the second embodiment with a ring attached thereto.

The exploded views of the claimed design are shown for convenience of illustration.
